UNITED STATES PATENT OFFICE

153,192

DESIGN FOR A BIRD HOUSE

Wilford W. Walton, Rockford, Ill.

Application June 21, 1946, Serial No. 130,903

Term of patent 7 years

(Cl. D31—2)

To all whom it may concern:

Be it known that I, Wilford W. Walton, a citizen of the United States, residing at Rockford, in the county of Winnebago and State of Illinois, have invented a new, original, and ornamental Design for a Bird House, of which the following is a specification, reference being had to the accompanying drawings, forming part thereof.

In the drawings:

Fig. 1 is a perspective side view of a bird house, showing my new design, and

Fig. 2 is a perspective view of the side thereof opposite that of Fig. 1, the bottom thereof being plain.

I claim:

The ornamental design for a bird house, substantially as shown and described.

WILFORD W. WALTON.
